Inventor,
Cornelius Berrian

United States Patent Office.

CORNELIUS BERRIAN, OF CLINTON CITY, IOWA.

Letters Patent No. 81,738, dated September 1, 1868.

IMPROVED MACHINE FOR PRESSING BRICKS.

The Schedule referred to in these Letters Patent and making part of the same.

TO ALL WHOM IT MAY CONCERN:

Be it known that I, CORNELIUS BERRIAN, of Clinton City, in the county of Clinton, and State of Iowa, have invented a new and useful Improvement in Brick-Presses for Pressing Brick; and I do hereby declare that the following is a full, clear, and careful description of the same, reference being had to the accompanying drawings, and the letters of reference marked thereon.

The nature of my invention consists in so constructing the press that one motion of the working-lever presses the brick, and the movement of this lever back discharges the brick smoothly without any roping or gasing. Also, the same movement opens the mould to receive the concrete or clay for a new brick. Also, in so constructing the lid or cover to the mould, as that the movement of a lever up and down will easily open the cap or close it securely, as desired, thereby saving a great amount of time, and making a more perfect article than in the ordinary way.

In the drawings, the same letters refer to the same parts, in which drawings—

Figure 1 is an end elevation.

Figure 2, a vertical section, showing discharge-rods, &c.

Figure 3 represents a perspective view.

Figure 4, side view, showing the pitman and discharge-rods.

Figure 5, section showing brick pressed, and discharge-rod in gear to force it out.

Now, to enable others to construct and use my invention, I will carefully describe its parts and construction.

The letters refer to the various parts as follows:

A represents the frame of press.

B represents the cap or cover to mould-box.

C represents the brick.

D represents the bottom of mould.

E represents the lever to operate the cover B.

F represents the pitman to force the bottom up.

H represents the sides of brick-mould.

J represents a movable fulcrum to operate press.

K represents a shaft running through the machine, and has a square end to receive the socket of lever T.

L represents adjustable arms to work discharging-device.

N represents shaft attached to pitman F.

O represents slot in arm L to regulate throw of rods S.

P represents slot in frame to regulate the cap or cover.

R represents slot in discharge-rods for rest to slide in when the mould is opened for material.

S represents rods for forcing out the brick after it is pressed.

T, the operating-lever of the press.

U represents rests that fit on shaft N to press the brick, being attached to bottom of mould.

V represents the strap that confines pitman F to shafts N and K.

W represents a recess in frame to receive the cap or cover B when a brick is to be pressed.

X represents a rack, with teeth, to gear into the movable fulcrum J.

Y represents the bottom of machine.

Z represents a shaft that moves in the grooves marked 2, and regulates the cover or cap P when opening and closing it.

Now, the construction and operation of my invention are as follows:

I construct the frame A, and all the various parts of the machine, of any suitable material, of proper strength and proportion, and arranging the parts so as to work in the following manner:

The place to receive the material for pressing into brick is located in the top part of the machine, and the bottom of this mould or place for material is made movable, and in the drawings is marked D.

To fill the mould with material, place the device so that the bottom, D, will be in position, as shown at D', fig. 2. The supports of this bottom, D, rest on the shaft N. Having filled the mould, and placed on the cap or cover B, which is firmly held in its place by shaft Z and notch W, and taking hold of the lever T, fig. 1, and bringing it down to the position of T', dotted line, and the cog-gear in J meshing into the rack X, and carrying the lower end of the pitman F from the incline, as shown in fig. 1 and fig. 2, to that shown in fig. 3 and fig. 5, which raises the shaft N as much as the difference between the incline and the perpendicular, now, to gain a great pressure and more distance, the shaft K is put beyond the centre of J, as shown at K, fig. 1 and fig. 2, and when the lever T is brought down to T', fig. 1, the shaft K is directly over the centre of J, thereby, in passing from the point, as shown at K, fig. 1 and fig. 2, to that of K, fig. 3 and fig. 5, increasing the distance of the movement of the shaft N, consequently raising the bottom, D.

It will be observed here that the greatest pressure is just where it is wanted, for as the material is compressed, the leverage is increased by the pitman F and shaft K coming into a perpendicular line under the mould.

The cap or cover B is operated as follows: The rod or shaft Z passes from the quadrant 2, through the handle E, to the opposite side, to a similar quadrant. The handle E turns on a pin in an eye fast to frame, with a slot, so as to have a motion horizontally, as at P, fig. 2, so that by bringing the handle E up to a level, as shown at figs. 1 and 3, the cap B will go into the catch W, which, with the rod Z, holds it firmly while the brick is being pressed. To remove the cap, bring the handle down, and, by the motion given by the quadrant 2 and slot P, fig. 2, the cap is easily removed, and no injury done to brick, as in other machines.

To discharge the brick from the mould, I have invented the following method: I attach to the inside of the travelling-fulcrum J an arm, fitted by a slot on to shaft K, made fast to J by means of a bolt or screw in a slot, as at O, figs. 2 and 5. This slot allows the arm to be adjusted to fit the desired throw to be given to the rods S. These rods pass through or around the shaft N to the under side of the bottom of mould. When the brick is pressed, the arrangement will be as shown in fig. 5. By bringing the lever T back to its first position, the wrist in arm L will catch in the socket, and, as the fulcrum J turns back, this arm L will force the rods S up, thereby raising the bottom of the mould to the top, as shown at D, fig. 2, leaving the brick free and clean, as at C, fig. 2. The position of these rods will be as indicated in fig. 2.

To set the machine to make another brick, I have but to press against the rods S and the socket on the wrist slips off, and the wrist in arm L no longer holds up the rods S and bottom D, but by their own weight the rods S slide down on this wrist in the slot R, as indicated by dotted lines in fig. 2.

I find a great advantage in my device to cover the mould, as at B. The first motion, after the brick is pressed, is a sliding one, by which the adhesion of the material to the cover B is overcome smoothly, leaving the top of brick smooth and fair.

What I claim as new, and desire to secure by Letters Patent, is—

The combination and arrangement of cap B, shafts N and K, pitman F, rods S S, arm L, and travelling-fulcrum J, when constructed, arranged, and operating substantially as and for the purpose herein set forth.

CORNELIUS BERRIAN.
